DESIGN FOR A GAME BOARD FOR PIN BALL GAMES

Herbert G. Breitenstein, Chicago, Ill., assignor to Raymond T. Moloney, Chicago, Ill.

Application March 20, 1935, Serial No. 55,971

Term of patent 3½ years

To all whom it may concern:

Be it known that I, Herbert G. Breitenstein, a citizen of the United States, residing at Chicago, in the county of Cook and State of Illinois, have invented a new, original, and ornamental Design for a Game Board for Pin Ball Games, of which the following is a specification, reference being had to the accompanying drawing, forming part thereof.

Figure 1 is a plan view of my design for the game board for pin ball games; and,

I claim:

The ornamental design for a game board for pin ball games, as shown.

HERBERT G. BREITENSTEIN.
